(57) **CLAIM**

I claim the ornamental design for a wheel support member for bicycle carrier, as shown and described.

DESCRIPTION

FIG. 1 is a top, front, and right perspective view of a wheel support member for bicycle carrier showing my new design; FIG. 2 is a front elevational view thereof; FIG. 3 is a rear elevational view thereof; FIG. 4 is a left side view thereof; FIG. 5 is a right side view thereof; FIG. 6 is a top plan view thereof; FIG. 7 is a bottom plan view thereof; and, FIG. 8 is a bottom, rear and left perspective view thereof. The broken lines in the drawings illustrate portions of the wheel support member for bicycle carrier which form no part of the claimed design.
